**COMBINED MAGNETIC TAPE CASSETTE
TRANSPORT AND RADIO**Orville W. Larson, Elmhurst, Ill., assignor to Ampex
Corporation, Redwood City, Calif.

Filed June 1, 1971, Ser. No. 149,096

Term of patent 14 years

Int. Cl. D14—01

U.S. Cl. D26—14

FIG. 1**FIG. 2**

FIG. 1 is a front, top and left side perspective view of a magnetic tape cassette transport and radio, showing my new design; and

FIG. 2 is a bottom, back and right side perspective view.

I claim:

The ornamental design for a combined magnetic tape cassette transport and radio, substantially as shown and described.
